(57) CLAIM

I claim the ornamental design for pants, as shown and described.

DESCRIPTION

FIG. 1 is a left, front perspective view of pants, showing my new design;

FIG. 2 is a right, front perspective view thereof;

FIG. 3 is a left side view thereof;

FIG. 4 is a right side view thereof;

FIG. 5 is a front view thereof; and,

FIG. 6 is a rear view thereof.

The dot-dash broken lines define a boundary line to the claim, but form no part of the claimed design. The even length broken lines depict features and portions of the pants that form no part of the claimed design.
